W. H. KURTZ,
FURNACE ATTACHMENT,
APPLICATION FILED OCT. 9, 1919.

1,427,483.

Patented Aug. 29, 1922.

INVENTOR
William H. Kurtz
BY
Comad A. Dietrich
His ATTORNEY

UNITED STATES PATENT OFFICE.

WILLIAM H. KURTZ, OF BLOOMFIELD, NEW JERSEY.

FURNACE ATTACHMENT.

1,427,483.

Specification of Letters Patent. Patented Aug. 29, 1922.

Application filed October 9, 1919. Serial No. 329,459.

To all whom it may concern:

Be it known that I, WILLIAM H. KURTZ, a citizen of the United States, residing at Bloomfield, Essex County, in the State of New Jersey, have invented certain new and useful Improvements in Furnace Attachments, of which the following is a full, clear, and exact specification.

My invention relates to improvements in furnace attachments, and has for its object to provide an attachment for controlling the direction and supply of air passing through the air inlet of the fire door of a furnace, boiler, stove or other analogous apparatus. Further, said invention has for its object to provide a device of this character by means of which the air passing through the air inlet of the fire door of a furnace or other analogous apparatus, will be deflected so as to impinge upon the fuel bed adjacent the front of the furnace.

Further, said invention has for its object to provide a device of this character which may be readily and quickly attached to the fire door of a furnace, or other analogous apparatus.

Other objects will in part be obvious and in part be pointed out hereinafter.

To the attainment of the aforesaid object and end my invention consists in the novel details of construction, and in the combination, connection and arrangement of parts hereinafter more fully described and then pointed out in the claims.

In the accompanying drawing forming part of this specification, wherein like reference numerals refer to like parts.

Figure 1 is a side elevation, partly in section, showing a heating apparatus embodying one form of deflecting attachment constructed according to and embodying my said invention:

Fig. 2 is a detailed perspective view showing the fire door detached from the heating apparatus, and provided with said deflecting attachment, and

Fig. 3 is a bottom view, partly in section, of Fig. 2.

Heretofore, in the operation of furnaces, boiler stoves and the like, it has been the common practice to permit the current of air passing through the air inlet of the fire door to enter the fire pot in a direction substantially parallel with the surface of the fuel bed whereby the air will be distributed over the entire surface thereof. I have

found, by experiment, that a more economical consumption of the fuel is obtained if the incoming current of air, instead of being allowed to flow into the fire pot in the above described manner, is deflected so that it will be caused to impinge upon the fuel bed at the front of the furnace, or other analogous apparatus. The result is obtained by the device forming the subject matter of this invention.

Referring to the drawing 10 indicates a furnace of any suitable type and construction, comprising a firepot 11, provided with a fuel charging opening 12, and an opening 13 which communicates with the smoke stack or flue, through which the products of combustion pass from the fire pot 11. The fuel charging opening 12 is provided with a fire door 15, of the usual construction, having an air inlet opening 16 formed therein with which a damper 17 co-acts to control the flow of air therethrough. In rear of the air inlet opening 16, and spaced therefrom, is a baffle plate 18 of the usual type, having formed therein a plurality of holes 19 by means of which the current of air passing through the air inlet 16 is divided into a plurality of jets in the usual manner. The parts thus far described are old and well known in connection with the construction of furnaces, and the like, and more detailed description thereof is unnecessary.

In order to cause the air entering through the air let opening 16 of the door 15, to be deflected in such a manner that it will impinge upon the bed of fuel within the firepot 11 at the front of the furnace 10, I provide a deflector 20, preferably formed of sheet metal, adapted for attachment to the baffle plate 18 forming a part of the fire door 15.

As shown, the deflector 20, has a hood-shaped body portion comprising a main deflecting wall 21, and side walls 22, 22, provided with grooves 23, 23, adjacent their edges adapted to engage the ends of the baffle plate 18. The side walls 22, 22 of the deflector 20 are of increasing width from top to bottom in order that, when the deflector 20 is in position, the main wall 21 thereof will be inclined inwardly and downwardly with respect to the fire door 15. Lugs 24, 24 at the top of the deflector 20, engage the upper edge of the baffle plate 18 to hold the deflector 20 properly positioned thereon.

The deflector 20 may be readily and quickly placed in position upon the baffle plate 18 by causing the lower ends of the grooves 23, 23 to register with the ends of the 5 baffle plate 18, and then sliding the deflector 20 downwardly upon the baffle plate 18 until the lugs 24, 24 engage the upper edge thereof and thereby prevent further downward movement of the deflector 20. If the 10 upper portion of the fire door 15 overlies the baffle plate 18, and thereby prevents the attachment of the deflector 20 in the manner above described, the deflector 20 may then be attached by springing the side walls 23, 15 23 outwardly sufficiently to permit the ends of the baffle plate 18 to be received within the grooves 23, 23.

In use, the jets of air passing through the holes 19 in the baffle plate 18 strike the 20 inclined main wall 21 of the deflector 20 and are deflected downwardly so as to impinge upon the bed of fuel within the fire 25 pot 11 at the front thereof.

Having thus described my said invention 25 what I claim and desire to secure by Letters Patent is:—

1. In a boiler, the combination of a fire-door, and a baffle plate thereon, with a deflector comprising an inclined main deflecting wall and side walls, means along the 30 free edges of said side walls adapted to engage the ends of said baffle plate, and means on said deflector adapted to engage with said baffle plate for supporting the same upon 35 said baffle plate, substantially as specified.

2. In a boiler, the combination of a fire-door, and a perforated baffle plate thereon, with a deflector comprising a downwardly inclined main deflecting wall, tapering end walls extending therefrom, channel members 40 along the free edges of said tapering end walls adapted to engage said perforated baffle plate at its opposite edges, and means at the upper edge of said main deflecting wall adapted to engage with the upper edge 45 of said baffle plate to support said deflector in position thereon.

3. In a boiler, the combination of a fire-door, and a perforated baffle plate secured thereto, with a deflector comprising a downwardly and inwardly inclined main deflecting wall contacting at its upper edge with 50 said baffle plate, end walls extending from said main wall having vertical free edges, channel members upon said vertical edges 55 adapted to slidably engage the opposite edges of said baffle plate, and lugs extending from the upper edge of said main wall member and adapted to rest upon the upper edge of said baffle plate to support said deflector in position upon said baffle plate, 60 substantially as specified.

Signed at the city of New York, in the county and State of New York, this 27th day of November, one thousand nine hundred and eighteen.

WM. H. KURTZ.
